UNITED STATES PATENT OFFICE.

CHARLES J. PERRY, OF YONKERS, NEW YORK.

WIRE-COATING MACHINE.

1,357,470.

Specification of Letters Patent.

Patented Nov. 2, 1920.

Application filed February 17, 1919. Serial No. 277,442.

To all whom it may concern:

Be it known that I, CHARLES J. PERRY, a citizen of the United States, residing at Yonkers, Westchester county, and State of New York, have invented a certain new and useful Wire-Coating Machine, of which the following is a specification.

This invention is a machine for applying a coating to strands of wire prior to winding the latter upon spools for sale and distribution as a new article of manufacture.

In the art of coating wire, it is usual to lead or run the strands drawn from supply spools through a cleaning bath and a coating bath, the latter being usually a metal alloy (tin) in a molten condition, whereby the strands are coated with tin prior to winding such coated strands upon individual spools.

According to this invention, provision is made for the rapid interchange of empty spools for the filled spools in the machine, and for the substitution of one spool for another without stopping the rotation of the winding spindle, whereby the operations of replacing the wound spools with empty spools may be performed rapidly and by utilizing the services of unskilled laborers to the end that economy in manufacture is attained.

The improvement is directed, mainly, to a demountable winding spool, or a series of such spools, together with means for coupling said spool or spools to their respective spindles, said spool coupling means being operable by or responsive to the movement of the spool or spools in the act of mounting and dismounting the same; in other words, no separate operation of the clutching means is involved prior to or during the operation of substituting one spool for another.

Broadly stated, the invention involves means whereby a spool is coupled to a driving spindle when mounted thereon and is uncoupled or released from said spindle in withdrawing or dismounting the spool, which operations are performed without arresting the rotation of the spindle and, also, without requiring a separate operation of the clutching means.

More specifically stated, the invention embodies a spindle, a winding spool demountable from the spindle, a clutch device of one form or another carried by the spindle and engageable with said spool for effecting the rotation of said spool with the spindle, and

a pressure device of one form or another, preferably spring mechanism, the same acting to retain the demountable spool in contact or engagement with said clutch mechanism, it being preferred to so relate the pressure or spring mechanism to the spool that these parts (the spool and the pressure device) are both demountable from and replaceable upon the spindle.

Other functions of the invention and the advantages thereof will appear from the following detailed description taken in connection with the drawings, wherein—

Figure 1 is a side elevation partly broken away, of so much of a wire tinning machine as is necessary for an understanding of my invention.

Fig. 2 is an elevation looking at the right.

Figs. 3 and 4 are detail views in elevation and vertical section respectively of one form of clutch suitable for use in connection with the winding spool.

Fig. 5 is a sectional elevation on the line 5—5 of Fig. 6, and Fig. 6 is a vertical longitudinal section of one spool and a form of clutch illustrated in Fig. 1.

Fig. 7 is an elevation of another form of the spool and the clutch which may be employed.

As shown in Figs. 1 and 2, the means for coiling strands of wire upon a series of spools, or upon two series of spools, includes a main frame A, a series of spindles B, suitable means such as a gear train for imparting rotary motion to all the spindles, a traversing device including a frame C, and one or more series of guides D for directing the strands of wire individually to the winding spools. It should be stated, and so understood, that uncoated strands of wire are drawn from suitable supply spools, and conducted through an appropriate cleaning bath, and thence conducted to and through a coating bath, the latter being composed usually of a metallic alloy, such as tin kept in a molten condition by the application of heat thereto; but as the means for performing the foregoing operations are ordinary in the art, I have not deemed it necessary to illustrate the same herein, nor do I consider it desirable or necessary to further describe the same.

As shown, the frame A is vertically positioned, and as usual it is provided with bearings c for the spindles B, any desired number of which are employed, said spindles

being horizontally positioned and arranged in spaced parallel order. The spindles are driven simultaneously and in one direction, for which purpose I use a series of counter-shafts *a* in alternate relation to the spindles and mounted in frame A, each countershaft being between two adjacent spindles and being provided with a gear *b* in mesh with gears *b'* on the spindles B, said shafts *a* 10 and gears *b* *b'* constituting a gear train whereby the spindles are driven as required. One spindle is shown as having a stepped pulley B' for the accommodation of a belt for driving the spindles and gear train, but 15 obviously other forms of power transmitter than the pulley may be utilized.

The traversing frame C and guides D are or may be of any form suitable for the purpose, and motion is imparted to the frame 20 C by any means known in the art whereby the frame and the guides carried thereby are shifted as required for directing the individual wire strands with respect to the spools in order to coil said strands uniformly 25 and regularly upon the spools, but as the frame C and guides D together with the actuating means therefor are usual in the art, it is not considered necessary to further illustrate or describe the same.

30 The machine herein illustrated as a preferred embodiment of the invention is adapted for the reception and operation of two series of winding spools designated at E, F, one series E being located at one side 35 of the machine and the other F at the opposite side thereof, but it will be understood that the machine may be constructed to utilize one series of spools only, and that any desired number of spools may be employed 40 in each series, although the machine with the two series of spools is preferred because of the increased capacity thereby attained.

As shown, each spindle B is long enough to extend at the respective ends thereof 45 through the bearings *c* and beyond the opposite sides of the frame A, said extended or prolonged end portions of each spindle being adapted for the reception of two winding spools E F, one upon each end.

50 Each spool is in the form of a sleeve or hub with heads or flanges at the respective ends of the sleeve or hub; see Fig. 6, the heads being provided with axial openings *e* in alignment with the hub whereby the spool 55 is readily slipped upon the extended end portion of a spindle B and is in like manner withdrawn and dismounted therefrom, said end portion of the spindle being free from obstruction and exposed for ready access whereby the spool may with facility be mounted upon the spindle and be dismounted therefrom.

Various forms of coupling devices may be employed for coupling the spool to the 60 spindle for the purpose of imparting to said

spool the rotary motion of the spindle, but according to this invention said coupling means does not require to be operated independently of the spools, for the reason that said coupling becomes effective in the operation of mounting the spool upon the spindle, and, further, the coupling permits the spool to withdraw readily, all of which operations of mounting and dismounting the spool are performed without stopping the spindle. 70

The clutch shown in Figs. 5 and 6 embodies two members G G', the former being held fast on spindle B by a key *g* (or equivalent) whereas the latter is loose on the spindle, said clutch members being provided with teeth or shoulders *g'* for mechanically interlocking the loose member G' with the fast member G. The loose clutch member G' is slideable on the spindle for effecting the interengaging and release of the loose 80 member relatively to the fast member, and in addition to said provision for mechanically interlocking the two clutch members, the slideable loose member G' is provided with means for frictional engagement with 85 said demountable spool, in order that said spool may partake of the rotative movement of the spindle. As shown, the clutch member G' is provided with frictional material, such as rubber or the like, the same being 90 in the form of plugs H seated in recesses *h* of the member G' and thus fixedly and mechanically attached to said member. Any desired number of friction plugs may be used, four being shown in Fig. 5, and said 95 plugs are positioned to protrude beyond the exposed face of the clutch member G', so as to have the desired frictional engagement with the spool, no specified form of spool being required or necessary. 100

105 Experience shows that the friction material H becomes worn in the course of time so that the desired frictional contact is not obtainable between the spool and the clutch member on the spindle. In view of the fact 110 that the spindle is rotating continuously, and that the interchange of the spools must be effected without stopping the operation of the winding machine as an entirety, I have found that the mechanical clutch G G' 115 of Fig. 6 is a desirable adjunct to the machine, more particularly in case the friction face H is worn down to such an extent that the spool is not driven frictionally. In such a case I use a spool of the kind shown 120 in Figs. 3 and 4, the end face of which is provided with a dog *j'* adapted to enter a pocket as *j* in the loose clutch member G'. Obviously, the mechanical engagement of the spool E' with the clutch member G' 125 cannot be advantageously effected while the clutch rotates with the spindle. Accordingly, the loose clutch G' is shifted out of mechanical contact with the fast clutch member G which rotates with the spindle, and 130

thus the loose clutch member G' is permitted to remain stationary while the spool as E' is placed upon the spindle, the spring retainer I being fitted on said spindle by the 5 same operation. Now with the clutch G' at rest, the spool and retainer are moved along the rotating spindle so that the dog j' will either enter a pocket as j or be fitted between two of the friction plugs H on clutch 10 member G' , the spool and the retainer being pressed along the spindle so that the loose member G' is engaged mechanically with the member G and the spring retainer is gripped frictionally to the spindle so as to hold the 15 parts in the required position.

Provision is made for retaining the spool in frictional engagement with the clutch member, thus insuring the desired rotation of the spool with the spindle. Various forms 20 of pressure devices may be employed, the one herein shown being a spring retainer I , comprising a coiled spring reduced in diameter at one end portion, at i , in order that said spring retainer may frictionally grip the 25 spindle or an extension B^2 thereof. When using the coiled spring retainer, it is preferred to use a stem B^2 tapering at one end portion as at b^2 and threaded at the other end portion, see dotted lines at b^3 in Fig. 6, 30 said threaded part of the stem being screwed into a socket tapped in the extremity of spindle B , whereby the stem is attached fixedly to the spindle so as to partake of the 35 rotation thereof and to constitute an extension of the same, in axial alinement therewith, see Fig. 6. The spring retainer I is provided with a hand grip or other operating member i' attached in a suitable way to the reduced part i of the spring. The spring 40 retainer envelops the outer part of the extension B^2 of the spindle, so that the inner part of the retainer exerts pressure against the spool, a washer i^2 being interposed between the inner end part of the coiled spring 45 retainer and one face of the spool in order to minimize wear on the spool. The taper b^2 of the spindle extension permits the spool and the spring retainer to be readily slipped upon said spindle in mounting the spool 50 thereon, whereas the contracted outer part i of the spring retainer is adapted for such frictional engagement with the spindle extension as to preclude any loose movement of the retainer, the latter thus acting effectively in exerting pressure upon the spool 55 for holding the same into the desired frictional engagement with the friction plugs H of the loose clutch member G' .

The spring retainers and spools are used 60 on the respective end portions of the rotary spindle, and for this reason I find it desirable to wind one spring retainer to the right hand and the other spring retainer to the left hand, the retainers for the opposite ends of 65 each spindle being wound of opposite hands.

Now, when a proper retainer is shoved onto one end of the spindle, the frictional contact of the rotating spindle with the spring retainer has a tendency to expand the coiled retainer sufficiently to permit it to slide 70 easily along the spindle until the spool is shoved into frictional contact with the clutch member G' and the latter is engaged with clutch member G , hand pressure being applied to the grip i of the spring, but when 75 the hand pressure is removed from the spring, then the part i of said spring is in frictional contact with the taper b^2 of the spindle extension so that the spring is held by frictional engagement in a relatively 80 fixed position on the spindle.

The spool is thus rotated with the spindle until the desired amount of coated wire is coiled thereon, after which the attendant cuts the wire and thereafter proceeds to dismount the spool. This is done by pulling on the hand grip i' so as to dislodge the spring retainer and remove it from the spindle, the filled spool following the retainer or being pulled off the spindle, thereby dismounting said spool, at which time the clutch member G' slides along the spindle with the spool for a short distance and thereby disengages member G' from member G . The attendant now proceeds to replace the 90 filled spool with an empty one, and this is effected by sliding the empty spool upon the spindle until it contacts with the friction plugs of the clutch member G' . The spring retainer is replaced upon the spindle and 100 moved thereon into the desired contact with the spool, which movement positions said spool into frictional contact with clutch member G' and effects the mechanical interlock of clutch member G' with the complementary clutch member G , thus coupling the 105 spool to the spindle for rotating therewith, said spring retainer being frictionally held upon the spindle and exerting pressure 110 against the spool.

It should be stated that the number of spools in each series exceeds by one the number of strands to be coiled upon the spools, thus holding in reserve one spool. The strands of wire are coiled simultaneously on the spools, and when the latter are filled, the attendant proceeds to cut one strand and shift the latter from the filled spool to the reserve spool, after which the first filled spool is dismounted, replaced by 115 an empty spool and then the next strand is cut and shifted to said empty spool, and the operations are repeated until all the filled spools are removed and replaced by spools upon which the strands are undergoing the required coiling operations. As a result, the replacement of the spools is performed rapidly and with the expenditure of a small amount of labor, and as the machine continues in operation during such replace- 120 125 130

ment of the spools, a very considerable economy of time, labor and power is effected.

As stated, the forms of clutch may be modified; thus in Figs. 3 and 4, the clutch member G' is shown as being provided with a pocket or recess j , whereas the spool E' is provided on one head thereof with a dog j' , the latter being made fast to the spool, and 10 said spool being used in connection with a spring retainer as I , heretofore described. In dismounting the spool, the retainer and the spool are pulled off the spindle, the dog j' slipping freely out of the recess j of the 15 clutch member G' , but when the parts are replaced the dog j' on the spool fits into the recess j of the clutch member, the operations being the same as heretofore described.

A further embodiment of the invention is 20 shown in Fig. 7 wherein the spindle B is mounted in bearing c of frame A and a spool E^2 is mounted on the spindle or its extension B^2 . A single clutch member L is provided with a hub l so as to be fitted on 25 the spindle, said hub being provided with a binding screw m for clamping the clutch member fixedly to the spindle so as to partake of the rotary movement thereof. This clutch member, or as it may be termed a 30 friction disk, is provided with friction material o in the form of plugs seated in recesses of the member or disk as shown by dotted lines and thus fixedly attached thereto, and said friction plugs o are exposed for frictional engagement with the 35 end face of the spool E^2 . A spring retainer I composed of a wire coil provided with a hand grip i' is used in connection with the spool as heretofore described so as to exert 40 pressure against the spool and thus retain said spool in frictional contact with the member or disk L . The spring retainer and the spool are adapted for attachment to the spindle, and to be dismounted therefrom, as 45 heretofore described, but in this embodiment of the invention I am enabled to dispense with the clutch member G' or its equivalent, the part L corresponding to the part G except that said part G is now provided 50 with the friction plugs and is adapted for coöperation directly with the winding spool.

Having thus fully described the invention, what I claim as new and desire to secure by Letters Patent is:—

55 1. In a spooling device, the combination with a spindle, and a spool demountable therefrom, of clutch means rotatable with the spindle and coöperating with said spool, and a spring retainer demountable from the 60 spindle with said spool, said spring retainer being provided with means for frictionally gripping said spindle whereby the retainer is connected with the spindle to remain in operative position thereon independently of 65 separate fastening means.

2. In a spooling device, the combination with a rotating spindle, a demountable spool, and a clutch rotatable with said spindle and coöperating with the spool for imparting rotative movement thereto, of a spring retainer in operative contact with said spool for holding the latter in like relation to said clutch, said spring retainer being provided with means for frictionally gripping said spindle. 75

3. In a spooling device, the combination with a rotating spindle, and a clutch member rotatable therewith, of a demountable spool in frictional contact with said clutch member, and a spring retainer coöperating 80 with said spool for holding the latter in driving frictional contact with the clutch member, said spring retainer being provided with means for frictionally gripping said spindle, and said spring retainer being demountable with the spool from said spindle without arresting the rotation of the latter. 85

4. In a spooling device, the combination with a rotating spindle, and a clutch member rotatable therewith, of a demountable 90 spool in frictional contact with said clutch member, and a demountable spring retainer coöperating with said spool for holding the latter in driving contact with said clutch member, said retainer being provided with 95 means for frictionally gripping said spindle and said retainer being demountable with said spool from said spindle without arresting the rotary motion of said spindle.

5. In a spooling device, the combination 100 with a rotating spindle, and a clutch member, of a demountable spool coöperating with the clutch member, and a demountable retainer in operative relation to said spool, said retainer comprising a coiled resilient 105 member one portion of which is reduced in diameter and adapted for frictionally gripping the spindle whereby the retainer is held upon the spindle independently of separate fastening means and is adapted to be 110 removed and replaced without arresting the rotary motion of the spindle.

6. In a spooling device, a spindle provided with a tapering end portion, a clutch member rotatable with the spindle, a spool coöperating with the clutch member, and a coiled spring retainer provided with means for frictionally gripping said tapering end portion of the spindle, said spring retainer coöperating with the spool for holding it 115 in driving contact with the clutch member, and said spool and the retainer being demountable from the spindle without arresting the rotary motion thereof.

7. In a spooling device, the combination 125 with a rotating spindle, and a demountable spool, of a clutch member rotatable with the spindle, said clutch member being provided with friction material positioned for contact directly with an end face of said spool, 130

and a spring retainer coöperating with said spool for holding it in driving contact with said clutch member, said spring retainer having means for frictionally gripping said 5 spindle, said retainer and the spool being demountable from the spindle without arresting the rotary motion thereof.

8. In a spooling device, the combination with a rotating spindle, and a spool, of a 10 clutch member positioned on the spindle for frictional contact with one end face of said spool, and a spring retainer positioned on the spindle for contact with the other end face of the spool, said spring retainer acting 15 to apply pressure to said spool for retaining

the latter in driving contact with said clutch member, and said retainer having means for frictionally gripping the spindle.

9. In a spooling device, a rotatable spindle, a spool demountable therefrom, coupling means positioned for engagement with said spool to impart rotative movement thereto, and a spring retainer coöperating with said spool, said spring retainer being provided with means for frictionally gripping the spindle. 20 25

In testimony whereof I have hereunto subscribed my name this 15th day of February, 1919.

CHARLES J. PERRY.
